UNITED STATES PATENT OFFICE

167,999

INDUSTRIAL TRUCK

John G. Rideout, deceased, late of Chagrin Falls, Ohio, by Alice C. Rideout, administratrix, Chagrin Falls, Ohio, assignor to The Buda Company, Harvey, Ill., a corporation of Illinois

Application December 12, 1951, Serial No. 17,694

Term of patent 14 years

(Cl. D14—3)

To all whom it may concern:

Be it known that John G. Rideout, deceased, late a citizen of the United States and a resident of Chagrin Falls, county of Cuyahoga, State of Ohio, during his lifetime invented a new, original, and ornamental Design for an Industrial Truck, of which the following is a specification, reference being had to the accompanying drawing, forming a part thereof.

Fig. 1 is a side elevational view of an industrial truck showing his new design;

Fig. 2 is a rear perspective view; and

Fig. 3 is a front perspective view thereof.

What is claimed is:

The ornamental design for an industrial truck, substantially as shown.

ALICE C. RIDEOUT,
Administratrix of the Estate of John G.
Rideout, Deceased.
